DESIGN FOR A GAME DEVICE

Namee Monier, Brooklyn, N. Y.

Application December 2, 1936, Serial No. 66,264

Term of patent 7 years

To all whom it may concern:

Be it known, that I, Namee Monier, a citizen of the United States, residing at Brooklyn, in the county of Kings and State of New York, have invented a new, original, and ornamental Design for a Game Device, of which the following is a specification, reference being had to the accompanying drawing, forming part thereof.

In the drawing:

Fig. 1 is a plan view of a game device, showing my new design.

Fig. 2 is a front elevational view of same.
Fig. 3 is a side elevational view of the game device, as shown in Fig. 2; and

Fig. 4 is an elevational view of the side of the game device opposite to that shown in Fig. 3.

I claim:

The ornamental design for a game device, as shown.

NAMEE MONIER.
